CLAIM

The ornamental design for a wig grip band, as shown and described.

DESCRIPTION

FIG. 1 is a front perspective view of a first embodiment of a wig grip band, showing my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is a further front perspective view thereof, wherein the wig grip band is shown deployed on the head of a wearer; FIG. 9 is a rear perspective view thereof, wherein the wig grip band is shown deployed on the head of a wearer; FIG. 10 is a front perspective view of a second embodiment of a wig grip band, showing my new design; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; FIG. 17 is a further front perspective view thereof, wherein the wig grip band is shown deployed on the head of a wearer; and, FIG. 18 is a rear perspective view thereof, wherein the wig grip band is shown deployed on the head of a wearer. The broken lines in FIGS. 1-18 are for the purpose of illustrating portions of the wig grip band and environmental structure that form no part of the claimed design.
